UNITED STATES PATENT OFFICE.

FRANK A. JOSEPH, OF NAUGATUCK, CONNECTICUT, ASSIGNOR TO L. CANDEE & COMPANY, A CORPORATION OF CONNECTICUT.

METHOD OF MAKING FOOTWEAR.

1,382,649.

Specification of Letters Patent. Patented June 28, 1921.

Original application filed November 26, 1919, Serial No. 340,939. Divided and this application filed May 7, 1920. Serial No. 379,456.

To all whom it may concern:

Be it known that I, FRANK A. JOSEPH, a citizen of the United States, residing at Naugatuck, county of New Haven, and 5 State of Connecticut, have invented certain new and useful Improvements in Methods of Making Footwear, of which the following is a full, clear, and exact description.

This invention relates to rubber or other 10 waterproof footwear and more particularly to what are known in the trade as bootees and walrus, being a division of my prior application Sr. No. 340,939, filed November 26, 1919.

15 Heretofore in the manufacture of this kind of footwear the lining cut to shape was first applied to the last and then the quarters and gusset pieces were applied. After the complete assemblage of the shoe and its 20 vulcanization, and in order to strip the boot from the last, the lining had to be cut a considerable distance at each side from the upper edge downward and forward, to where the gusset disappears or blends into 25 the quarters. These two cuts, one on each side of the shoe and in the lining only, were extremely difficult to make after the vulcanization of the shoe and while it was still on the last. Sometimes the cutting tool was 30 inadvertently projected through the superimposed quarters. And while it was absolutely necessary to cut the lining to remove the bootee from the last, it left a weak place at the bottom or disappearing point of the 35 gusset. Furthermore the edges of the lining had to be subsequently trimmed to make the article neat enough to satisfy the demands of the trade and even after trimming a ridge was left on each side of the pocket or 40 gusset.

The present invention aims to improve 45 rubber footwear having foldable or expandable portions known as pockets or gussets. It seeks to avoid the weak apex in the old 50 gusset construction, to eliminate the flanking ridges or seams, and thereby to improve both the appearance and the durability of the article. It also eliminates entirely the operation of cutting the inner lining in 55 order to remove the shoe from the last and to permit the gussets to function in the completed article which operation was not only difficult but also resulted in the ruin of many 60 shoes otherwise satisfactory and marketable.

The method of the present invention also enables the outer wall portions of the shoe upper, usually in the form of quarters, to be assembled on the lining along with the gussets while the several parts are in a substantially flat condition. 55

Gusseted footwear according to the present invention has an inner lining in one or more sections which is continuous and unbroken at and adjacent the fold lines in the expandable portion and is preferably without a break in its continuity from a line well within the margin of the gusset to a line on the quarter in rear of the fold in the expandable portion when in its normal folded condition. In the manufacture of the 70 articles the gussets and quarters are preferably applied to the lining to form the upper complete and then mounted on a last or tree. After this the shoe is completely assembled but during or after its assemblage 75 and before vulcanization the gussets are temporarily secured in the folded condition desired in the finished articles. Then the shoes are vulcanized. After vulcanization the gussets are freed or released and the article is removed from the last without any 80 difficulty and without seam or break in the lining at or adjacent the fold lines in the gussets.

These are the objects of the present invention and other objects thereof will appear in the description of the embodiment of the invention illustrated in the accompanying drawings in which:

Figure 1 is a plan view of a substantially 90 complete upper as it appears from the interior when flattened out and shows the superimposed relation of the inner lining, interlining, quarters, and gusset halves the plies of one side being stripped back to show the 95 relation thereof.

Fig. 2 is a horizontal cross section through a completed shoe midway the length of the gussets.

Fig. 3 is a side elevation of a shoe partly 100 in vertical section.

Fig. 4 is a perspective showing how the gusset is temporarily strapped to the last in a folded condition.

The drawing shows a preferred embodiment of the invention calculated to meet present demands of the trade. In the preferred embodiment the lining is made in 105

sections 1 and 2 which are lapped and seamed at the front and rear median lines of the finished article. Quarters 3 and 4, preferably but not necessarily provided with reinforcing interlinings 5 and 6 are joined to gusset halves 7 and 8 to form fastening flies 9 and 10, which may be eyeleted as shown to receive laces or which may have buckles or other fastening devices applied thereto. A toe lining (not shown), vamp 12, front stay 13, tap sole 14 and heel 15 with a few other parts of well-known form complete the make-up of the shoe.

The parts are assembled in the following manner: The lining sections are first cut to shape and notched or otherwise marked at the points 16, 18, 17 and 19 to indicate where adhesive tabs 20, 21 are to be attached and the gussets folded in a subsequent operation. The rear edges of the lining sections 1 and 2 are lap seamed together as indicated at 22. The quarters 3—4 with interlining 5—6 and a counter 23 are then assembled on the lining 1—2 together with the gusset half sections 7—8, the gusset halves being joined directly to the front edges of the quarters and for some little distance inward to form the fastening flies 9—10, while the intermediate portions of the quarters and half gussets are stuck to the lining sections directly. Preferably, however, the front free margins of the inner lining and of the gusset halves are left unsecured as shown in Fig. 1 at the right so that when the thus completed upper is mounted on a last and the toe lining and vamp then assembled, the front edges of the inner lining may be lapped directly on each other as shown at 24 Fig. 2 and the front edges of the gusset halves may be seamed together in abutting or lapped relation. This serves to break the several joints and to give strength at the front median line of the upper which may be further strengthened and a finished appearance imparted by applying a front reinforcing stay 13.

Friction tabs 20, 21 and 25 are located between the lining and the outer wear portions of the upper. This is preferably done after seaming the lining sections 1 and 2 together at the rear but it may be done at any convenient time. The tabs are preferably of the short length shown so as not to interfere with manipulation in the assemblage of parts but they may be made longer if desired. If the tabs are made short as shown other pieces of friction tape are adhered to them and so lengthened the tabs are drawn tight about the last, tab 25 at the rear center being pulled diametrically over the top of the last 26 and adhered to the front median line of the gusset while tabs 20 and 21 are pulled backwardly around the sides of the last and adhered to the tab 25 adjacent its junction with the lining at the rear. In this way each gusset is held folded during vul-

canization in the condition desired in the finished articles, vulcanization of course effecting a more or less permanent set or fixation of the goods.

When the footwear has been completely assembled, that is when the tap sole foxings and other component parts have been put together on the last and the various seams rolled or "stitched" together, the articles are vulcanized in any suitable manner. After the articles have been vulcanized and are practically ready for the market the operator has merely to break the tabs to remove the shoe from the last, the tabs being trimmed or broken off readily when convenient.

By reason of the continuous one-piece lining at or adjacent the fold lines in the expandable portion of the upper, great strength is imparted to the apices of the foldable portions of each gusset where, in removing the vulcanized article from the last or in donning or doffing footwear in use, the article is subjected to great strain. The continuity of the lining sections of the quarters where they overlie the folds in the gusset in use (which will be clear from a scrutiny of Fig. 2) also insures comfort in wear and enhances the appearance of the article. And continuity of the lining sections also avoids the weak and lumpy seams of prior footwear, of the same type. In the method the tedious, difficult, unsatisfactory and ruinous operation of cutting a continuous lining of exactly the same length from front to back as the last according to the prior practice has been avoided and eliminated. The necessity of trimming the first cut, which was necessarily ragged, so as to finish the seam neatly has also been avoided.

The foregoing relates to a method of manufacture which I prefer but it is to be distinctly understood that the invention is not limited to described details thereof. The inner lining for instance could be made in one piece or in more than two pieces but for reasons such as waste in cutting and additional operations these alternatives are not at present deemed desirable. The particular form of the upper is also immaterial. Instead of two quarters with attached half gussets it might be possible to form the outer wear portions of the upper complete in one piece but this I do not deem desirable. Other changes might be made without departing from the principle of the present invention which broadly as understood is thought to reside in the elimination of seams or ridges, particularly in the vicinity of the folds of the gusset and in the idea of temporarily holding the gussets folded during the vulcanization of the article and preferably also during the assemblage of the toe lining and vamp on the completed upper, after the upper has been positioned on the last. Another im-

portant principle of the method involved in the present invention is in the assemblage of the gusset halves and quarters on the lining while in a substantially flat condition which is valuable because the parts may be put together in the right position by operators less skilled and less expensive than lastmen. Obviously the tabs for holding the gussets folded may be applied at other times and to other parts than those mentioned without departure from the principles of this invention whose scope should be ascertained by reference to the claims.

And while the method of the present invention is of especial value in the manufacture of footwear without a seam or joint in the lining adjacent the fold or folds in its expandible portion, some of the advantages in the method would be realized in temporarily holding the shoe folded with the lining sections applied to the upper in other ways than that described. The invention, therefore, in its broadest aspect would comprehend lining the component parts of the upper according to the old practice, that is to say, separately lining the quarters and gusset.

Having thus described my invention what I claim and desire to protect by Letters Patent is:

1. In the manufacture of rubber footwear having foldable portions, assembling the upper forming parts including the foldable portions off the last, mounting the upper thus assembled on a last, completing the assemblage of the parts of the article on the last, temporarily securing the folded portions in their final position, subsequently vulcanizing the articles, and thereafter freeing the foldable portions of the upper.

2. In the manufacture of rubber footwear having gussets, assembling the upper form-

ing parts including outer rubberized portions and gussets in a flat condition, mounting the upper thus far assembled on a last, completing the assemblage of the footwear on the last, temporarily securing the gussets folded in the condition desired in the finished footwear, subsequently vulcanizing the articles, and thereafter releasing the folded gussets and removing the articles from the lasts.

3. In the manufacture of rubber footwear with foldable gussets, shaping half lining sections, indicating thereon lines of gusset fold, securing the lining sections together, assembling quarters and gusset portions on the inner lining thus formed, mounting the upper thus far formed on a last, completing the article on the last and securing the gusset temporarily folded, subsequently vulcanizing the article, and finally releasing the folded gusset and removing the article from the last.

4. In the manufacture of rubber footwear having one or more gussets, assembling the component parts of the article on a last, temporarily securing the gussets folded before vulcanization in the position desired in the finished article, and subsequently vulcanizing the article while the gussets are held temporarily folded.

5. In the manufacture of rubber footwear having one or more gussets, assembling the component parts of the article on a last, attaching tabs to the gussets and anchoring the tabs to hold the gussets folded in substantially wearing position on the last, and subsequently vulcanizing the article while the gussets are held folded.

Signed at New Haven, Connecticut, this 4th day of May, 1920.

FRANK A. JOSEPH.
